[57] CLAIM

The ornamental design for a rug, as shown.

DESCRIPTION

FIG. 1 is a front elevational view of a rug showing our new design;

FIG. 2 is a top plan view, the bottom plan being identical thereof;

FIG. 3 is a side elevational view, the opposite side being identical thereof; and,

FIG. 4 is a rear elevational view thereof.

It is understood that the cross-hatch pattern shown in part is continuous throughout in FIGS. 1 and 4.

FIG. 2

FIG. 1

FIG. 3

FIG. 4
